UNITED STATES PATENT OFFICE.

LOUIS LANE, OF HABANA, CUBA.

CASEMENT-WINDOW.

1,370,325.

Specification of Letters Patent. Patented Mar. 1, 1921.

Application filed September 18, 1919. Serial No. 324,521.

To all whom it may concern:

Be it known that I, LOUIS LANE, a citizen of the United States, and at present residing at Habana, Cuba, have invented a new and Improved Casement-Window, of which the following is a full, clear, and exact description.

My present invention relates to windows of the general type known as "casement windows", and more particularly relates to a metal window frame and sash.

The general object of the invention is to provide frame parts of novel forms and cross sections, and so arranged that the "weathering" of the sash is made tight without expensive hand-fitting necessary with the usual frames for the assemblage of the various members.

A more specific object of the invention is to provide an embodiment of the same that may be produced from few elements of simple form and resulting in a strong and weather-tight casement by the ordinary methods of manufacture employed in the quantity production of metal sashes and window frames.

It may be stated that in windows of the type referred to flat contacts alone have not been sufficient in "weathering" the sash except where very carefully fitted, while sloping contacts which have been devised for "weathering" the sash are usually effective only when used at the sill but less effective when used at the head. Also while such sashes could be drawn tight at the lock bars, they were apt to be loose at the head or hinge jamb unless very specially fitted.

The stated objections and others as will appear are overcome by the novel construction of casement window hereinafter particularly described and claimed.

Reference is to be had to the accompanying drawings forming a part of this specification, it being understood that the drawings are merely illustrative of one example of the invention.

Figure 1 is a front view of a casement window embodying my invention and having two swinging sashes;

Fig. 2 is an enlarged horizontal section on the line 2—2, Fig. 1;

Fig. 3 is an enlarged vertical section on the line 3—3, Fig. 1;

Fig. 4 is a detail in horizontal section at the lock side of the sash in a window em-

ploying a single sash, the view being given to show the preferred form of the jamb member of the window frame in a single-sash construction;

60

Fig. 5 is a fragmentary horizontal section at the lock sides of two adjacent sashes when employed with a frame having no mullion;

Fig. 6 is a detail in vertical section on the line 6—6, Fig. 2, the view being given to show the ball bearing at the bottom of the window at the hinge side.

In carrying out my invention according to the illustrated example, a window frame 70 is provided designated generally by the numeral 10, and a sash or sashes designated generally by the numeral 11. The side bar 12 of the sash 11 at the hinge side of the sash, terminates at the outer portion in a 75 curved hinge member 13, which fits a fixed hinge member 14 rounded in cross section to conform to the interior curved surface of said hinge member 13. The fixed hinge member 14 is formed on or secured to the 80 jamb 17 of the window frame, said fixed hinge member being here shown as having a web 15 secured by rivets 16 to said jamb. Also in the jamb 17, is a concave depression 17^a spaced from the fixed hinge member 14, presenting a curved way in which the hinge member 13 has movement, said hinge member and the seat 17^a being concentric with the hinge member 14.

The side bar 12 of the sash has a leg 90 or flange 18 directed laterally inward toward the inside of the window and its edge is adapted when the sash is closed, to have close contact with flange 19 rigid with the jamb 17 and here shown as consisting of a 95 separate angle bar secured by the rivets 16 to the jamb.

The elements 13, 14, 17^a, 18 and 19 extend the full height of the window from the bottom cross bar to the head or top 100 cross bar and the arrangement serves to produce a weather-tight joint.

A tubular metal stop strip 20 is secured to the flange 18 fastened in the illustrated example by having nuts 20^a therein which 105 are engaged by screws 20^b.

At the lock side of each sash the vertical side bar 21 thereof is formed with a transversely-curved terminal 22, corresponding essentially with the hinge member 13, and 110 adapted to engage a mating rigid member on a mullion or on an adjacent sash.

In the form shown in Fig. 2, a fixed member 23 engaged by the member 22 of the sash is secured by a rivet 24 or other suitable securing means, to the stem 25 of a 5 mullion 26, T-shaped in cross section, there being members 23 at opposite sides of the web 25 to be engaged by the respective sashes.

In Fig. 4, the side bar 21 at the lock side 10 of the single sash engages with a member 23 secured to or formed upon the jamb 26^a, Z-shaped in cross section.

In the form shown in Fig. 5, where no 15 mullion is employed, the transversely curved member 22 at the lock side of one sash receives a transversely curved flange on a plate 28 secured by rivets 29 or other means to the correspondingly curved edge portion 22^a of the adjacent sash 21^a. The 20 flange 27^a of said adjacent sash has secured thereto a plate 30 to cover the space between the sashes at the inside, said plate advantageously being connected by a transverse post or elongated rivet 31, to the plate 28, 25 said rivet 31 having a sleeve 32 thereon to space the plate 28 and plate 30. The flange 27 of the adjacent sash at the lock side is adapted to have close engagement with the plate 30. In the form shown in Fig. 2, the 30 flanges 27 of the sashes contact with the mullion 26.

The window at the top and bottom is formed to correspond with the side members 13 and 22, in making the sash weather-tight at the top and bottom. Thus the head or top cross bar 33 of the window frame, which preferably is Z-shaped in cross section, has rigid therewith a bead 14^a corresponding in cross section essentially with 35 the fixed hinge member 14, and the top cross bar 12^a of the sash has a transversely curved member 13^a corresponding essentially with the hinge member 13 and with the curved lock side member 22 to conform to the 40 surface presented by the bead 14^a. Also the flange 18^a at the inner side of the sash bar 12^a is adapted to lie close against the depending flange 19^a of the head 33.

The bottom cross bar 34 of the window 50 frame similarly is Z-shaped in cross section and has rigid therewith a bead 14^b rounded in cross section to be engaged by a corresponding curved terminal 13^b on the bottom cross bar 12^b of the sash. The bar 34 presents an upstanding flange 19^b with which the adjacent flange 18^b on the bar 12^b contacts.

The various window frame members and 60 sash frame members are properly reinforced by angle irons and stiffening plates, there being angle irons 35 in the bars 12 and plates 36 on the flanges 19. Similarly the flange 19^a has a stiffening plate 36^a, and the adjacent top bar 12^a of the sash has an angle 65 piece 35^a. A corresponding plate 36^b and

angle bars 35^b are provided on the bars 34 and 12^b.

It is to be understood that the angles of the upright and horizontal members of the window frame and sash frame are joined in 70 any approved manner. In practice also the sash has bottom support at the hinge side by a ball bearing indicated in Fig. 6, comprising a bearing plate 37 on the bottom cross bar 34 of the frame, and having an 75 annular race for the balls 38, the lower edge of the curved hinge member 13 having an arcuate wear plate 39 applied thereto to rest on the balls.

The character 20° indicates stops on the 80 flanges 27. The stops 20° are adjustable by having slots to receive the fastener bolts or screws.

The above described construction comprises an effective weather-tight joint at the 85 hinge side, while insuring free and easy movement of the sash on the hinge. An effective weather-tight joint is also effected on the lock side, and the contact of the inwardly-directed flanges on the sash bars 90 with the adjacent flanges on the frame at the inner side of the window, insures a tight engagement of the sash both at the inside and the outside of the window.

It will be observed also that the frame 95 parts are of simple form, strong and durable, and comparatively few in number.

I would state in conclusion that while the illustrated example constitutes a practical embodiment of my invention, I do not limit 100 myself strictly to the mechanical details herewith illustrated since manifestly the same can be considerably varied without departure from the spirit of the invention as defined in the appended claims.

Having thus described the invention, what is claimed as new is:

1. A casement window including a window frame, a fixed vertical hinge member on a jamb thereof extending substantially from the bottom to the head of the frame and presenting a transversely rounded surface, and a sash with a side bar at the hinge side terminating in a transversely curved flange portion extending from the top to the bottom of the sash mating the curvature of the fixed hinge member, said curved flange portion extending into said arcuate clearance space and partially embracing said first-mentioned member to have a weather-tight engagement therewith and having turning movement on said fixed member in the swinging movements of the sash.

2. A casement window including a window frame, a fixed vertical hinge member on a jamb thereof extending substantially from the bottom to the head of the frame and presenting a transversely rounded surface, and a sash with a side bar at the hinge side terminating in a transversely curved flange 125

- portion extending from the top to the bottom of the sash mating the curvature of the fixed hinge member and partially embracing the same to have a weather-tight engagement therewith and having turning movement on said fixed member in the swinging movements of the sash, said jamb presenting a concave depression forming an arcuate clearance space between the jamb and the surface of the fixed hinge member for the movement of the hinge member on the sash.
3. A casement window including a frame having thereon at the jamb and lock sides, vertical fixed members presenting in cross section a rounded exterior and extending from top to bottom of the window, and a sash having side bars terminating in flange portions curved in cross section in the arc of a circle mating the surfaces of said fixed members and extending from top to bottom of the sash, said curved flange portion at the hinge side partially embracing the adjacent fixed member of the frame to turn thereon, and the similar curved flange portion at the lock side of the sash being adapted to contact with the curved surface of the adjacent fixed frame member.
4. A casement window including a window frame having on the sides and on the top and bottom bars thereof, for substantially their full length, fixed members presenting in cross section rounded outer surfaces, and a sash having thereon at the sides and at the top and bottom, flange portions curved in cross section and positioned to engage, respectively, said fixed members, there being an arcuate space between one of the fixed members at a side of the window frame and the opposed surface presented by said frame, and that curved flange portion at the hinge side of the sash engaging and being turnable on the adjacent fixed member of the frame, the engagement of the several flange members with the fixed members forming a weather-tight joint therewith.
5. A casement window including a window frame having a fixed hinge member presenting in cross section an outer surface curved in the arc of a circle and extending from top to bottom of the window, and a sash having at the hinge side a frame bar terminating in a flange portion extending from top to bottom of the sash and curved in cross section in the true arc of a circle and partially embracing said fixed hinge member with weather-tight engagement, said flange portion being turnable on said fixed hinge member in the swinging of the sash, said sash having a flange disposed transversely to the general plane of the sash, and said window frame having a member disposed in a direction corresponding with the general plane of the window in position for the free edge of said sash flange to make a weather-tight contact therewith when the sash is closed.
6. A casement window including a window frame having on the sides and on the top and bottom bars thereof, for substantially their full length, fixed members presenting in cross section rounded outer surfaces, and a sash having thereon at the sides and at the top and bottom, flange portions curved in cross section and positioned to engage, respectively, said fixed members, that curved flange portion at the hinge side of the sash engaging and being turnable on the adjacent fixed member of the frame, the engagement of the several flange members with the fixed members forming a weather-tight joint therewith, the respective sash members having flanges disposed transversely to the general plane of the window, and the window frame having flanges on the respective members thereof disposed in the general plane of the window and adapted to receive the contact of the last-mentioned flanges on the sash.
7. A casement window including a window frame having fixed members on the jambs thereof above the hinge side and lock side of the frame and extending from top to bottom thereof, said members presenting in cross section rounded surfaces, and a sash having at the hinge side and at the lock side frame bars terminating in flange portions extending from the top to the bottom of the sash and curved in cross section in the arc of a circle to conform to and partially embrace said fixed members, to form a weather-tight joint, that flange portion at the hinge side being turnable on the adjacent fixed member in the swinging of the sash, said sash having flanges at both the hinge side and lock side and extending substantially from top to bottom of the sash and said window frame having on the jambs thereof at the hinge side and lock side, flange members disposed in directions corresponding with the general plane of the window and adapted in the closed position of the sash to receive the contacts of the transversely flanged members on the sash.

LOUIS LANE.
